LIQUID MIXING FAUCET ATTACHMENT

Thomas C. Knaebel, Kirkwood, and Carl J. Deutsch, Rock Hill, Mo., assignors to Carl J. Deutsch, Bela Deutsch, and Herman Deutsch, doing business as Standard Machine & Manufacturing Co., St. Louis, Mo.

Application May 5, 1955, Serial No. 35,840

Term of patent 14 years

(Cl. D91—3)

FIG. 1.

FIG. 2.

FIG. 4.

FIG. 3.

Fig. 1 is a top plan view of the liquid mixing faucet attachment, showing our new design;

Fig. 2 is a front elevational view thereof;

Fig. 3 is a bottom plan view thereof, and

Fig. 4 is a side elevational view thereof.

We claim:

The ornamental design for a liquid mixing faucet attachment, substantially as shown.
